UNITED STATES PATENT OFFICE.

HUGH G. BONNER, OF CLAY CENTER, NEBRASKA.

HEN'S NEST.

1,093,602.

Specification of Letters Patent. Patented Apr. 21, 1914.

Application filed December 16, 1912. Serial No. 737,150.

To all whom it may concern:

Be it known that I, HUGH G. BONNER, a citizen of the United States, residing at Clay Center, in the county of Clay and 5 State of Nebraska, have invented certain new and useful Improvements in Hens' Nests; and I do declare the following to be a full, clear, and exact description of the invention, such as will enable others skilled 10 in the art to which it appertains to make and use the same.

This invention relates to improvements in hens' nests.

One object of the invention is to provide 15 a hen's nest having an improved means for detachably securing the nest to a suitable support.

Another object is to provide a nest having 20 an improved construction and arrangement of cover whereby a setting hen may be confined on the nest without injury or inconvenience to the hen.

With these and other objects in view, the 25 invention consists of certain novel features of construction, and the combination and arrangement of parts as will be more fully described and claimed.

In the accompanying drawings; Figure 1 is a perspective view of my improved hen's 30 nest showing the same arranged and supported in position for use; Fig. 2 is a central vertical longitudinal section of the nest showing the cover thereof in closed position for confining a hen on the nest; Fig. 3 is a 35 rear end view of the nest; Fig. 4 is a detail perspective view of the rear end of a nest showing a slight modification of my invention.

My improved hen's nest may be formed of 40 any suitable material but is preferably constructed of sheet metal and comprises a body 1, the sides and bottom of which are formed from a sheet of metal, the ends of which are bent upwardly and spaced a suitable distance apart to form sides 2 while the curved intermediate portion of the metal sheet forms the bottom 3 of the nest. The front or outer end of the nest is formed by a substantially semi-circular plate 4 which preferably extends upwardly a little more than half way the distance between the bottom and top of the body 1 of the nest. The rear end of the nest is formed by a plate 5 which is preferably arranged at a slight angle and extends from the bottom to the top

of the body as shown. The end plates 4 and 5 may be soldered or otherwise rigidly secured to the end edges of the body of the nest.

The upper end of the back end plate 5 of 60 the nest is extended and bent rearwardly and thence downwardly to form a nest supporting hook 6 which is adapted to be engaged with a bar 7 or other suitable support which, if desired, may be a part of the structural framework of the hen house. The supporting hook 6 is reinforced midway between its ends by a stiff supplemental supporting hook 8 of strap iron or the like the inner end of which is riveted or otherwise 70 rigidly secured to the upper portion of the back plate 5 while the bill of said hook 8 closely fits the outer side of the hook 6 as shown.

The nest is preferably provided with a 75 cover 9 which, in the present instance, is shown and is also preferably in the form of a sheet metal plate having on its front and side edges depending flanges 10 which, when the cover is closed down on top of the nest, fits over the sides and front end thereof as clearly shown in Figs. 2 and 3 of the drawings.

The inner end of the top plate of the cover is preferably notched adjacent to the inner edge of the side flanges and said notched inner edge of the plate is turned downwardly to a slight extent as shown at 80 11 thereby forming a ventilating opening at the inner end of the nest when the cover is closed. A pivot rod 12 extends transversely 85 across the nest near the inner end thereof and has its ends inserted through the sides 2 of the nest and through the adjacent rear ends of the side flanges 10 of the cover, whereby the latter is pivotally secured to the 90 nest.

The cover when swung upwardly is held in an open position by a hook 13 secured to the side of the hen house or to a suitable support and which is adapted to be engaged with a staple 14 arranged in one 100 side of the cover 9 as clearly shown in Fig. 1 of the drawings. By providing the cover 9, it will be seen, that when the latter is closed for confining a hen on the nest air and light will be supplied to the hen through the space 105 left between the lower edge of the front flange of the cover and the upper edge of the front end piece of the nest as clearly shown in Fig. 2 of the drawings. By providing supporting and attaching hooks for 110

the nest as herein shown and described, it will be seen that the latter may be readily engaged with a horizontal bar or other support and when desired may be readily removed from said support for cleaning or other purposes.

In Fig. 4 of the drawings is illustrated a slight modification of my idea. In this view, the rear end 5' of the nest 1' is provided with hooks 6' at each upper corner said hooks being adapted for the same purpose as the flange 6 hereinbefore described.

A nest constructed in accordance with my invention will be strong, durable, strictly sanitary and vermin proof and may be inexpensively manufactured.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

A hen's nest comprising a sheet metal body having a front end extending part way up the sides, a rear end plate secured to the rear ends of said sides and having its upper edge extended and bent to form a supporting hook, a reinforcing hook whose shank is secured to said rear end and whose bill fits closely over the supporting hook, a cover comprising a metal sheet having depending side flanges and its rear edge notched adjacent the flanges and bent inwardly to form a ventilating opening between it and said hooks, and a cross rod underlying the rear portion of the cover and passing through said sides and flanges, for the purpose set forth.

In testimony whereof I have hereunto set my hand in presence of two subscribing witnesses.

HUGH G. BONNER.

Witnesses:

JACOB SIPULAR,
L. F. FRYAR.
